OUTDOOR EXPOSED LOUVER

Arthur D. Hemphill, Minneapolis, Minn.

Application July 18, 1946, Serial No. 684,475

3 Claims. (Cl. 160—44)

1

My invention relates to outdoor exposed louvers and has for its object to provide a louver of well-known construction wherein the face frame which is exposed to the weather is a single member formed of some non-corrosive material and in which the louver opening formed through the central portion of the face plate is provided at its corners with specially constructed drainage notches to inhibit accumulation of water and ice between the face plate and the back frame of the louver.

Louvers of the type herein disclosed, particularly for use in ventilating systems for forcing warm air out of rooms or buildings, comprise a box-like frame member for holding the louver blades and a face plate member for securing the louver to the wall through which the box-like frame part of the louver extends for effecting the ventilating arrangement. The face plate and the screen across the opening, therefore, will be exposed to weather and quite frequently will be wet with rain, snow, sleet or the like.

The opening through the face plate is customarily closed by a mesh screen, the edges of which come between the face plate and the edges of the louver frame.

A serious difficulty has been encountered in connection with the placement of such louvers, by reason of the fact that water from rain, sleet, melting snow and the like runs down along the vertical wires of the screen member and creeps in between the wooden frame of the louver and the overlying parts of the face plate.

This water, particularly along the lower edge of the louver opening and to a degree along the side edges and even the top edge, tends to remain in a layer over the edges of the screen and the edges of the louver frame to which the screen is attached.

The result has been that freezing has at times loosened or broken the face plate, that rusting of the screen will ultimately take place, and not infrequently rotting of the frame member may and does take place. Also where the face plate is made of strips of material secured to the louver frame there has been a tendency for these strips to warp and separate at the joints.

I have discovered a very simple means of overcoming these difficulties. First I construct the face plate of the louver of some strong, hard and durable non-corrosive material such as a rigid composition board of which "masonite" is an example, and I make this face plate of one integral continuous piece with the opening to the screen and the louver blades cut from this piece.

Second, I provide at the corners of this opening notches cut back from the edges of the face plate in both directions so the notches come out over the edges of the union of the face plate with

the louver frame and across the ends of the vertical screen strands and have the effect of bringing about gravity drainage of water which otherwise would accumulate along the screen edges between the face plate and the edges of the louver frame.

It is a principal object of my invention therefore to provide a face plate for the louver which will be formed of one single unbroken piece, preferably of some hard, durable and non-corrosive material, such as a rigid composition board, and which has formed along the regions of its central part a louver opening, backed by a mesh screen over the louver blades.

It is a further object of my invention to form at the corners of the face plate means which enables the moisture to be drained away from the line of junction of the face plate and the louver frame.

It is a further object of my invention to form these drainage means as notches at the corners of the louver opening, cut back in both directions into the face plate to points on the screen along the lines of junction of the face plate and the louver frame, with the screen between them.

The full objects and advantages of my invention will appear in connection with the detailed description thereof which will now be given in the following specification, and the novel features of my invention by which the advantageous and useful results above enumerated are obtained will be particularly pointed out in the claims.

In the drawings illustrating an application of my invention in one of its forms:

Fig. 1 is a front plan elevation view of my improved louver showing in particular the face plate itself, the louver opening through it, the notches therein at the corners of the opening, and the screen back of the face plate at its edges and across the opening.

Fig. 2 is a longitudinal sectional elevation of the louver taken on line 2—2 of Fig. 1.

Fig. 3 is a transverse sectional view of my invention taken on line 3—3—3 of Figs. 1 and 2.

As illustrated, a louver box is formed of any suitable material, which comprises end walls 10 and 11, side walls 12 and 13 and holding strips 14 and 15, as indicated specifically in Fig. 3. This frame in and of itself is open at top and bottom.

The side members are provided with a series of slots 16 which receive the ends of louver blades 17 as best shown in Fig. 3. The slots 16 extend diagonally across the side walls 12 and 13 and are held in position by the holding strips 14 and 15 as clearly indicated in Figs. 2 and 3. The box-like structure above described is held together by staples 18 as indicated generally in Fig. 3. Also by nails 27 across the side walls 12 and 13 to the end walls 10 and 11. The louver blades

17 are preferably formed of the same material as is the face plate of the louver. Preferably this material should be a rigid composition board of which "masonite" is an example. This face plate, indicated generally by the numeral 19, is secured to the upper edges 20, 21, 22 and 23 of the end walls 10 and 11 and side walls 12 and 13 by means of end fasteners 24 and side fasteners 25, the latter being indicated in dotted lines at 26 on Fig. 3.

As clearly indicated in Figs. 2 and 3, a face plate 19 stands upon the end walls 10 and 11 and side walls 12 and 13 of the louver frame substantial distances for being positioned against the outside surface of any wall through which the louver is made to extend. Holes 28, 29, 30 and 31 extend through the face plate along longitudinal and transverse central lines by means of which the face plate and the louver is secured in its permanent position.

A highly important feature of my invention consists in a peculiar type of notch formed at each corner of the cut-out portion 32 of the face plate 19.

These notches, indicated generally by the numeral 33, are at the exact corners of cut-away portion 32 and comprise square cut-out parts 34 and 35 extending into each other at 36 and having side shoulders 37 and 38. A screen 39 of wire mesh or any suitable material overlies the top edges of end walls 10 and 11 and side walls 12 and 13 and is held at its upper edges between said top edges and the face plate 19 as clearly shown in Figs. 2 and 3.

While the notches 33 are shown as cut square on each of their sides with square shoulders 37 and 38, it is within the scope of my invention to slope the walls of the notches in either direction, as may be found desirable, and also to slope the shoulders out of the perpendicular if desired.

The operation of these notches is to permit gravity drainage thereinto and therefrom of water accumulation on the screen 39. The water runs down the longitudinal screen threads and similarly reaches the notches, from which it drains out over the corners thereof and drops away from within the confines of the cut-away portion 32.

This prevents the accumulation of water in the space occupied by the edges of the screen between the face plate 19 and the top edges of the end pieces 10 and 11 and side pieces 12 and 13 of the louver frame, and prevents injury to the louver by reason of freezing of water in those confined spaces or by rusting of the screen or rotting of the frame edges.

The primary advantage of my invention resides in the provision of a one-piece face plate with means formed therein to insure drainage of water from the space occupied by the edges

of the screen between the face plate and the top edges of the ends and sides of the louver frame.

Another advantage resides in the use of a one-piece face plate formed with corner notches to secure drainage of water from the space between the face plate and the top edges of the ends and sides of the louver frame, where the screen edges are held, and in which there are no joints in the 10 face plate which may open up to permit water to pass through the face plate itself.

I claim:

1. A louver construction, comprising a one-piece plate having a cut-away portion at its central part, a louver frame open at both sides, a screen covering said cut-away portion and held in position at its edges between the edges of the louver frame and the face plate, and means associated with said face plate and the screen 15 for establishing drainage of water from the space occupied by the edges of the screen between the edges of the louver frame and the face plate.

2. A louver construction, comprising a one-piece plate having a cut-away portion at its central part, a louver frame open at both sides, a screen covering said cut-away portion and held in position at its edges between the edges of the louver frame and the face plate, and notches at 25 the respective corners of said cut-away portion which extend across the longitudinal strands of the screen at the ends of its edges for establishing drainage of water from the space occupied by the edges of the screen between edges of the louver frame and the face plate.

3. A louver construction, comprising a one-piece plate having a cut-away opening at its central part, a louver frame open at both sides, a screen covering said cut-away portion and held in position at its edges between the edges of the louver frame and the face plate, and notches 40 at the respective corners of said cut-away portion which extend across the longitudinal strands of the screen at the ends of its edges for establishing drainage of water from the space occupied by the edges of the screen between edges of the louver frame and the face plate, said notches being cut-in beyond the edges of the cut-away opening, with shoulders extending at right angles to each other at each end of each 45 notch.
